(57) **CLAIM**

The ornamental design for a photo kiosk with interactive stations, as shown and described.

DESCRIPTION

FIG. 1 is a right front perspective view of a photo kiosk with interactive stations in accordance with a first embodiment of the design;

FIG. 2 is a left rear perspective view of the design of FIG. 1;

FIG. 3 is a front view of the design of FIG. 1;

FIG. 4 is a top view of the design of FIG. 1;

FIG. 5 is a right front perspective view of a photo kiosk with interactive stations in accordance with a second embodiment of the design;

FIG. 6 is a left rear perspective view of the design of FIG. 5;

FIG. 7 is a front view of the design of FIG. 5; and,

FIG. 8 is a top view of the design of FIG. 5.

The broken lines within the bounds of the photo kiosk with interactive stations represent unclaimed portions of the design that form no part of the claimed design.
